TRAILER HITCH PLATE

Richard W. Rollins, Joliet, Ill., assignor to Nash Bros. Co., Joliet, Ill.

Filed Mar. 4, 1971, Ser. No. 121,231

Term of patent 14 years

Int. Cl. D12—10, 16; D8—08
U.S. Cl. D14—6 C

FIG. 1

FIG. 2

FIG. 3

FIG. 4

FIG. 1 is a perspective view of a trailer hitch plate embodying my design;

FIG. 2 is a top plan view;

FIG. 3 is a rear view;

FIG. 4 is a view of one side, the other side being essentially the same in appearance.

I claim:

The ornamental design for a trailer hitch plate, as shown and described.
